JAMES B. COFFIN, OF ASHLAND, OHIO.

Letters Patent No. 67,499, dated August 6, 1867.

IMPROVED WASHING MACHINE.

The Schedule referred to in these Letters Patent and making part of the same.

TO ALL WHOM IT MAY CONCERN:

Be it known that I, JAMES B. COFFIN, of Ashland, in the county of Ashland, and State of Ohio, have invented a new and useful Improvement in Washing Machines; and I do hereby declare that the following is a full, clear, and exact description thereof, which will enable those skilled in the art to make and use the same, reference being had to the accompanying drawings, forming part of this specification, in which—

Figure 1 is a vertical central section of my improved washing machine.

Figure 2 is a horizontal section of the same, taken through the line $y-y$, fig. 1.

Figure 3 is a detail sectional view of the same, taken through the line $x-x$, fig. 1.

Figure 4 is a detail view of the under side of the pounder.

Similar letters of reference indicate corresponding parts.

My invention has for its object to furnish an improved washing machine, so constructed and arranged that the operator may stand erect and work the machine with both hands, and which will do its work quickly and thoroughly, whatever be the quality of the clothes being washed; and it consists in the arrangement of the strips or rubbers upon the bottom of the tub; in the construction of the pounder, and in the construction and arrangement of the parts by which the pounder is operated.

A is an ordinary wash-tub, to the bottom of which are attached sockets B to receive the legs C, which should be of such a length as to raise the tub to a convenient height. To one side of the tub, at its upper edge, is attached a block D, which may be in one or more pieces, and which should have a shoulder formed upon its inner edge to receive the end of the board E. One end of the board E is hinged to the block D, and its other end rests upon the upper edge of the opposite side of the tub, as shown in fig. 1. To the board E are attached three posts F, the upper ends of which are connected and held in their proper relative positions by the top board G. The rear post f' is slotted, and in the slot thus formed is pivoted the rear end of the lever H, the pivoting-pin passing through a slot in the end of the lever and through one or the other of the holes through the post f' , so that the height of the forward end or handle of the lever may be adjusted according to the height of the operator. The main part of the lever H is made in two parts, which are connected to each other by the side pieces h' , so as to form a space for the passage of the shaft or handle I of the pounder J. The handle I has a groove formed around it to receive the collar K, by which it is connected to the lever H. The collar K is made in two pieces, and in substantially the form shown in fig. 3, and may be removed and attached by removing one or both of the side pieces h' . L is a rubber or equivalent spring, the upper end of which is attached to the top board G, and its lower end to the rear post of the lever H, as shown in fig. 1. M is the handle, which crosses the forward end of the lever H at right angles, and is connected to it by a rubber spring, N, to relieve the jar when the pounder is forced down upon the clothes. The handle or shaft I works up and down through holes in the boards E and G, as shown in fig. 1, and to its lower end is attached the pounder J, which is a circular disk having notched cleats attached to its lower surface. Four of the cleats (marked j^1) extend radially from the centre of the disk to its circumference, and the spaces between these are each occupied by two or more cleats j^2 , placed at right angles to the cleats j^1 , as shown in fig. 4, so that the cleats j^2 in adjacent spaces may stand at right angles to each other. O is a circular disk attached to the centre of the bottom of the tub, from which disk radial cleats P extend to the sides of the tub, so that the rubber attached to the bottom of the said tub may represent a wheel, as shown in fig. 2.

I claim as new, and desire to secure by Letters Patent—

1. The combination of the block D, board E, posts F, board G, and lever H with each other and with the tub A, substantially as herein shown and described and for the purpose set forth.
2. The collar K, constructed as shown and described, in combination with the handle I and side pieces h' of the lever H, substantially as and for the purpose herein set forth.
3. The combination of the rubber or equivalent spring L with the board G and lever H, substantially as herein shown and described and for the purpose set forth.
4. Attaching the handles M to the lever H by means of a rubber or equivalent spring N, substantially as herein shown and described and for the purpose set forth.

JAMES B. COFFIN.
